UNITED STATES PATENT OFFICE

152,201

DESIGN FOR A COMBINED CIGARETTE PACK AND MATCH HOLDER

John L. Mack, Sr., Chicago, Ill.

Application October 15, 1947, Serial No. 141,910

Term of patent 14 years

(Cl. D85—2)

To all whom it may concern:

Be it known that I, John L. Mack, Sr., a citizen of the United States of America, residing at Chicago, in the county of Cook and State of Illinois, have invented a new, original, and ornamental Design for a Combined Cigarette Pack and Match Holder, of which the following is a specification, reference being had to the accompanying drawing, forming a part thereof.

Fig. 1 is a perspective view of a combined cigarette pack and match holder showing my new design;

Fig. 2 is a top elevational view thereof;

Fig. 3 is a rear elevational view thereof;

Fig. 4 is a side elevational view thereof; and

Fig. 5 is another side elevational view thereof showing the side opposite that in Fig. 4.

I claim:

The ornamental design for a combined cigarette pack and match holder, as shown.

JOHN L. MACK, SR.
